[57] CLAIM

The ornamental design for a cartridge for game machine, as shown and described.

DESCRIPTION

FIG. 1 is a top, front and right side perspective view of a cartridge for a game machine showing my new design; FIG. 2 is a bottom, rear and right side perspective view thereof;

FIG. 3 is a rear elevational view thereof;

FIG. 4 is a top plan view thereof;

FIG. 5 is a front elevational view thereof;

FIG. 6 is a left side elevational view thereof;

FIG. 7 is a bottom plan view thereof;

FIG. 8 is a top, front and right side perspective view of a second embodiment of the cartridge illustrated in FIG. 1;

FIG. 9 is a bottom, rear and right side perspective view of the embodiment disclosed in FIG. 8;

FIG. 10 is a top, front and right side perspective view of a third embodiment of the cartridge disclosed in FIG. 1; and

FIG. 11 is a bottom, rear and right side perspective view of the embodiment disclosed in FIG. 10.

The left side elevational view of the second embodiment of the cartridge is a mirror image of the right side thereof.

The left side elevational view of the third embodiment of the cartridge is a mirror image of the right side thereof.
